UNITED STATES PATENT OFFICE

172,509

LINK CHAIN FOR A NECKLACE OR THE LIKE

Alfred Philippe, Scarsdale, N. Y., assignor to Trifari, Krussman & Fishel, Inc., New York, N. Y.

Application September 21, 1953, Serial No. 26,879

Term of patent 7 years

(Cl. D45—16)

To all whom it may concern:

Be it known that I, Alfred Philippe, a citizen of the United States of America, residing in Scarsdale, county of Westchester, and State of New York, have invented a new, original, and ornamental Design for a Link Chain for a Necklace or the like, of which the following is a specification, reference being had to the accompanying drawing, forming part thereof.

Fig. 1 is a plan view of a link chain for a necklace or the like showing my new design.

Fig. 2 is an edge view thereof.

I claim:

The ornamental design for a link chain for a necklace or the like, substantially as shown.
